UNITED STATES PATENT OFFICE.

EZRA W. HASENPFUG, OF EAST CLEVELAND, OHIO, ASSIGNOR TO THE CHAMPION SAFETY LOCK COMPANY, OF GENEVA, OHIO, A CORPORATION OF OHIO.

SASH-FASTENER.

SPECIFICATION forming part of Letters Patent No. 744,755, dated November 24, 1903.

Application filed December 12, 1902. Serial No. 134,970. (No model.)

To all whom it may concern:

Be it known that I, EZRA W. HASENPFUG, a citizen of the United States of America, and a resident of East Cleveland, in the county of Cuyahoga and State of Ohio, have invented certain new and useful Improvements in Sash-Fasteners, (Case No. 2,) of which the following is a specification, reference being had to the accompanying drawings, forming 10 a part thereof.

My invention relates to improvements in sash-fasteners, and has for its object the provision of a device of this character adapted, preferably, to be formed from sheet-steel and 15 assembled from a few simple parts so designed as most effectively to accomplish the unctions of a sash-lock.

My improved device is of the type having a pivoted cam-like operating-lever for adjusting the window-sashes when coöperating with or acting upon a hook-shaped keeper, which parts are respectively mounted upon the two meeting-rails of said sashes.

Before entering upon a detailed description 25 of my improved sash-fastener I may briefly set forth the characteristics thereof by stating that the same is comprised of but five parts—the chambered case-plate, mounting the flanged operating-lever by means of an 30 integral tubular pivot and washer, and two flat suitably-shaped springs and the coacting keeper, against which the flanged lever operates. These parts are stamped by suitable dies, preferably from sheet-steel of suffi- 35 ciently heavy gage, the case-plate in the adopted form having an integral boss or stop formed upon its upper face for staying the operating-lever, the said lever and tubular pivot and washer being riveted together and the springs 40 being so bent or shaped as to stay themselves in the case-plate and securely mount the operating-lever and its pivot therein.

Further particulars of construction and operation will be readily understood by referring 45 to the accompanying drawings, illustrating the preferred embodiment of my invention, wherein—

Figure I is a plan view of the complete sash-fastener. Fig. II is a bottom view of the case-plate and the parts mounted therein. Fig. 50

III is a vertical sectional view on line 3 3, Fig. I. Fig. IV is a front view of the keeper. Figs. V and VI, respectively, are side and plan views of the integral pivot and washer; and Fig. VII shows in plan and sectional 55 views a case-plate of modified form.

Throughout these drawings and the accompanying description the same characters of reference are employed to designate similar parts or structural details.

It will be quite obvious to those conversant with the art that although my improved sash-fastener is of excellent design the several parts constituting it are of extremely simple and strong construction and are easily formed 65 or stamped from any suitable sheet metal.

The oblong chambered case-plate *a* is pierced near its ends by two countersunk screw-holes *a*² for seating the screws by which it may be attached to the meeting-rail of the 70 lower sash. A boss or stop *a*³ is struck up from the upper face of the case-plate, which otherwise is flat, to form a flush bearing for the operating-lever *b*. A circular opening provided centrally in said case-plate serves 75 to accommodate the tubular portion of the integral pivot and washer *c*, which mounts said lever upon the case-plate. This operating-lever is rearwardly flanged to afford an inclined and eccentric actuating edge or way 80 *b*² for operating the keeper *d* to raise and fasten the sashes. A thumb-piece *b*³ is provided by which the lever is manually moved, while lateral recesses *b*⁴ indent the front edge of the lever and accommodate the stop *a*³ alter- 85 natively in either of the extreme positions of the said lever. Segmental countersunk holes *b*⁵ are centrally formed in the flat portion of the lever to receive the upper extremities *c*² of the pivot *c*, the said extremities being up- 90 set therein after their insertion, thus making the parts practically integral.

The part *c* is shown in detail in Figs. V and VI of the drawings, and comprises two shouldered segmental uprights *c*³, extending 95 through the case-plate to form a laterally-flattened tubular pivot for the lever and a substantially circular head or washer *c*⁴ for mounting the lever upon the case-plate. This is accomplished by means of the flat springs 100

e e, which are of sufficient width to pivotally mount the lever closely upon the case-plate when said springs are mounted edgewise and interiorly between the top of the case-plate and the head of the pivot, as seen in Fig. III. The springs *e e* are C-shaped, having both their ends outwardly bent, after the manner shown in Fig. II, and together conform to the interior outline of the case-plate, fitting snugly therein, particularly at the ends, between the depending rim thereof and the depressions formed by the countersunk screw-holes *d²* upon either side of the pivot and beneath its integral head or washer. By this means the springs are held securely in place without providing special parts in the case-plate to accommodate them, and accordingly this type of spring contributes materially to the simplicity and cheapness of the structure. Especially is this true in a stamped case-plate, since the provision of lugs or equivalent parts therein (quite common in cast case-plates for retaining in position the straight flat springs) would necessitate cutting openings or depressions in the sides or top of the stamped case-plate, which obviously would be both undesirable and difficult. If desired, a single heavy spring might be employed, thus reducing the several component parts to four; but I prefer the arrangement herein shown. Similarly the integral tubular pivot and washer *c* is of simple and strong construction and in effect becomes a part of the operating-lever when united as set forth. It affords a large bearing for the operating-lever and is stiff and rigid, being connected thereto at two relatively distant points. The hooked keeper *d* likewise is quite elementary in form, having a chambered base *d²*, provided with the necessary screw-holes, and an angularly-shaped hook or extremity *d³*, rising above an indentation or recess in the base. This extremity is shaped to conform to the flanged operating-lever.

When the sash-fastener is given a fine finish, I have found that the rotation of the operating-lever is liable to scratch or mar the surface of a perfectly-flush case-plate, and accordingly I have devised a modification of the latter which avoids this disadvantage and also makes the operation of said lever somewhat easier. This modification (illustrated in Fig. VII) provides a slightly-raised annular bearing-face or platform about the central opening of the case-plate, whereon the operating-lever freely turns, said bearing-face *a⁴* being of considerably less height than the boss *a³* in order that the lever may be

checked by said boss or stop in the manner described.

When properly mounted upon the meeting-rails of window-sashes, the several parts form a simple, cheap, and effective sash-fastener. The springs *e e*, bearing laterally upon the cut-away portions of the tubular pivot, tend to maintain the operating-lever in either of its extreme positions in engagement with the stop *a³*. Upon turning the operating-lever beneath the hooked extremity of the keeper the latter rides upon the eccentric flanged actuating edge *b²* of said lever. The continued rotation of the lever serves to adjust the sashes so that their meeting-rails are brought into alinement and also are drawn into close engagement with each other, in which position they are locked.

Having now described the preferred embodiment of my invention, I desire to claim the features which I believe to be new therein, as follows:

1. In a sash-fastener, the combination with a chambered case-plate having an elevated central platform *a⁴*, of an operating-lever pivotally mounted thereon to swing above the level of said case-plate, thereby reducing friction and avoiding the defacement of said case-plate, and a spring or springs within the case-plate adapted to swing the operating-lever to either of its normal positions, substantially as set forth.

2. In a sash-fastener, the combination with a mounting-plate, of an operating-lever, and a rigidly-attached tubular pivot part therefor, formed of sheet metal and serving to mount the operating-lever, substantially as set forth.

3. In a sash-fastener, the combination with a case-plate, of a pivoted operating-lever, and a depending tubular pivot therefor; all of said parts being formed of sheet metal, and the pivot and lever being rigidly united, substantially as set forth.

4. In a sash-fastener, the combination with a chambered case-plate, of a flanged operating-lever, an integral tubular pivot and washer rigidly attached thereto, and a spring-mounting for the said pivot and operating-lever serving to secure them rotatably to the case-plate, substantially as set forth.

Signed at Cleveland, Ohio, this 6th day of December, 1902, in the presence of two subscribing witnesses.

EZRA W. HASENPFLUG.
